UNITED STATES PATENT OFFICE.

HOWARD H. CRAWFORD, OF DETROIT, MICHIGAN, ASSIGNOR TO PINES WINTERFRONT COMPANY, OF CHICAGO, ILLINOIS, A CORPORATION OF DELAWARE.

COOLING APPARATUS FOR AUTOMOBILES.

Application filed October 8, 1925. Serial No. 61,292.

The invention relates to cooling apparatus for motor vehicles and the like, and has among its objects the provision of thermostatic control means for efficiently regulating 5 the cooling system. A further object resides in the provision of thermostatic control means for restricting or by-passing the water to assist in warming up the motor quickly in the warmer seasons of the year when 10 the use of shutters is impractical.

The invention further includes a radiator shutter thermostatically operated whereby the shutter is actuated to admit cooling air to the radiator after the cooling water has 15 been brought up to the desired temperature by reason of the by-pass. The invention also affords a construction permitting convenient detachment of the shutter, as when the motor vehicle is operated in the warmer 20 seasons of the year, and at the same time permitting the thermostatic control to function whereby the engine is quickly warmed and efficiently operated.

With these and other objects in view, the 25 invention resides in the novel features of construction and combination and arrangements of parts as more fully hereinafter described and claimed.

In the drawings illustrating a preferred 30 embodiment of my invention:

Figure 1 is a side elevational view of an internal combustion engine and radiator showing my invention applied thereto;

Fig. 2 is a sectional view on a larger scale 35 of the thermostatic apparatus;

Figs. 3 and 4 are sectional views taken on the planes 3-3 and 4-4 of Fig. 2, and

Fig. 5 is a sectional view through the radiator shutter attachment taken on the plane 40 of the line 5-5 of Fig. 2.

Fig. 1 illustrates a typical automobile power plant comprising the motor 6, radiator 7 and water connections 8 and 9 for connecting the radiator with the cylinder jacks 45 sets of the engine. The circulation may be thermo-siphon, or through a water pump, as shown.

Referring to Fig. 2, the upper tank 10 of the radiator is formed with transverse partitions 11, 12, dividing the tank 10 into chambers A, B and C. The partition 11 constitutes the end wall of a cup-shaped shell 13 having an outwardly extending flange 14 at

its other end. The other partition 12 is suitably secured in said shell so as to be removable therewith as a unit. The flange 14 of the shell is secured to a plate 15 which supports the entire thermostatic unit in the tank or water box 10. This end plate covers an opening in the rear wall of the tank 60 through which the unit is inserted, this end plate being suitably secured to a flange 17 extending from the tank around this opening. The end plate 15 is provided with a packed bearing 18 in which slides a valve 65 stem 19 carrying valves 21 and 22 which are urged toward the partition 12 by spring 20 to substantially cover the by-pass ports 23 and 24, respectively, therein. The partition 12 is preferably formed with a centrally disposed relatively large opening 25 forming a seat for a valve 26. Between the valve 26 and the valve stem 19 a by-pass thermostat 27 is positioned within the chamber C, for actuating the valve stem 19 and valves 21 75 and 22. The valve 26 is actuatable through a valve stem 28 by a main thermostat 29 located in chamber B. The partition 11 is provided with a plurality of openings 31 permitting passage of water therethrough. 80 It will be understood that the thermostats 27 and 29 may each consist of a single thermostatic unit or of a plurality of thermostatic wafers, as shown.

The chamber A communicates with the 85 cooling surfaces of the radiator, while chamber C receives the cooling water from the engine through the conduit 8. This conduit, or the rubber hose portion thereof is connected to a nipple 32 extending from the end plate 15.

Associated with the above-described thermostatic mechanism is a radiator shutter attachment designated 34 in its entirety. This device comprises a fenestrated shell 35 in 95 which are mounted a plurality of pivotally supported shutters 36. When the shutter attachment is mounted on the radiator, these shutters 36 are automatically actuated by the above described thermostatic mechanism. 100 This operative connection is preferably established through a long slender rod 38 which passes through one of the openings in the radiator core. The rear end of this rod is connected by a pivot 39 to an operating lever 41 which extends down across the end of 105

the tank 10. The upper end of this lever is pivoted at 42 to pivot bracket 43 extending from the end plate 15. The protruding valve stem 19 bears against an enlargement 5 44 formed in this lever.

The front end of the rod 38 may be operatively connected to the radiator shutters in any preferred manner. In the arrangement shown in Figures 2 and 5, the rod connects to an arm 46 mounted on a horizontal shaft 47. This shaft has pivotal support in bearings 48 carried by the shell of the attachment. The other end of this shaft carries an arm 49 which has pivotal attachment 15 with the link 51 connecting all of the shutters together. The shutters are preferably urged towards closed position by the spring 52 connected to the upper end of the link. When the shutter attachment is removed 20 for warm weather driving, the rod 38 is released from the operating lever 41 by removal of the pivot 39, thereby permitting removal of the shutter attachment and rod, and the operating lever 41 may also be removed, if desired, by releasing the pivot 42.

In operation, before the engine is started up the shutters 36 will normally be closed and the thermostats 27 and 29 contracted, the valves 21 and 22 substantially closing 30 ports 23 and 24, respectively. After starting up the engine the cooling water entering chamber C by the conduit 8, exerts a heating influence on the by-pass thermostat 27 expanding the same sufficiently to uncover 35 ports 23 and 24. Between the interval of starting the motor and the actuation of thermostat 27 a limited quantity of water may be by-passed from chamber C to the lower part of the motor in order to prevent undue 40 resistance to the circulating pump which is ordinarily provided with cooling systems. However, the same result may be obtained by allowing a limited leakage through the partition 12 so as to render such by-pass unnecessary. This may be accomplished by 45 providing relatively small vents 55 in the periphery of the partition 12. It will thus be noted that in starting the motor the circulation of the cooling water is restricted 50 in the chamber C, beyond the limited amount allowed to leak past the partition 12 as aforesaid, until the water is raised to a predetermined temperature at which time the thermostat 27 will function to unseat the 55 valves 21 and 22 to by-pass the water in restricted quantity to the chamber B.

The cooling water will thereafter be caused to circulate through the openings 31 into chamber A. When the water in chambers A and B has been raised to a predetermined temperature suitable for opening the shutters, the thermostat 29 will expand, acting through valve stem 28 to unseat valve 60 26 to allow an additional quantity of water 65 to pass from chamber C through the open-

ing 25 to chamber B, thus producing substantially unrestricted circulation throughout the system. The valve stem 28 also acts at the same time, through the valve stem 19 to rock the lever 41 on its pivot 42, causing 70 opening of the shutters 36. When the motor vehicle engine is shut off, the cooling water will lose its heat permitting the thermostats 27 and 29 to contract, whereby the shutters are closed.

In the warmer seasons of the year, the shutter attachment 34 may be removed, the lever 41 preferably being disconnected at the pivot 42. It will thus be noted that the thermostats will function as before, serving 80 to by-pass the water in restricted quantities until the cooling system is thus quickly raised to the desired temperature in chambers B and A, whereupon the thermostat 29 will function to unseat the valve 26 affording 85 relatively unrestricted flow of the cooling water through the entire system.

It will thus be noted that it is not necessary to warm up the entire volume of cooling water in the system to bring up the efficiency of the motor to the desired point, since the use of the by-pass or retarding thermostatic valves stops the water circulation and allows the water in the top of 90 the motor around the combustion chamber 95 to reach an efficient temperature quickly, both in the warmer seasons when the shutters are not in use and in the colder season when the thermostats additionally operate such shutters.

The invention affords the use of a shutter giving the maximum opening since there are no parts of the apparatus to obstruct the available cooling area, rendering it possible to have the shutters attached until the 100 weather becomes quite warm.

A further advantage resulting from my invention is in positioning the thermostats in the water where they are not subject to the many cooling influences to which they 110 would otherwise be exposed.

While it is believed that from the foregoing description, the nature and advantage of my invention will be readily understood, I desire to have it understood that I do not 115 limit myself to what is herein shown and described and that such changes may be resorted to when desired as fall within the scope of the claims.

I claim:

1. In combination with an engine cooling system comprising a radiator and a cooling liquid circuit including the engine and radiator, a plurality of communicating chambers included in said cooling liquid circuit, a thermostat in one of said chambers, a second thermostat in another of said chambers controlled by the first said thermostat, and a plurality of shutters controlled by said second thermostat.

2. In combination with an engine cooling system comprising a radiator and a cooling liquid circuit including the engine and radiator, means for restricting the flow of cooling liquid in starting the engine until a portion of the liquid in proximity to the engine has been raised to a predetermined temperature, a chamber, said means adapted to thereafter by-pass a portion of the heated liquid to said chamber, and thermal means associated with the chamber actuatable after the liquid therein has reached a predetermined temperature for causing substantially unrestricted flow of liquid in the circuit. 70
- 10 3. In combination with an engine cooling system comprising a radiator and a cooling liquid circuit including the engine and radiator, a by-pass thermostat adapted to restrict the flow of liquid until the liquid contacting therewith is raised to a predetermined temperature, a second thermostat controlled by said by-pass thermostat, movable shutters associated with the radiator, and means actuatable by one of said thermostats for moving the shutters. 80
- 20 4. In combination with an engine cooling system comprising a radiator and a cooling liquid circuit including the engine and radiator, a plurality of communicating chambers included in said cooling liquid circuit, a thermostat in one of said chambers, valve means actuated thereby to admit said liquid to control a thermostat in another of said chambers, movable shutters associated with the radiator, and means actuatable by the second said thermostat for moving the shutters. 85
- 25 5. In combination with an engine cooling system comprising a radiator and a cooling liquid circuit including the engine and radiator, movable shutters associated with the radiator, actuating means for moving the shutters, thermostatically controlled means for regulating the flow of cooling liquid in said circuit and for controlling a second thermostat to actuate said shutters, said actuating means being readily removed from its normal operative position without disturbing the operation of said thermostatically controlled means. 90
- 30 6. In combination with an engine cooling system comprising a radiator and a cooling liquid circuit including the engine and radiator, a plurality of intercommunicating chambers included in said circuit, one of said chambers having communication with the cooling liquid from the engine, a by-pass thermostat within the latter chamber, a by-pass valve actuatable by said by-pass thermostat for by-passing the liquid to another of said chambers, a valve stem slidably extending through a wall of said chamber, a main valve on said stem, a main thermostat in the second said chamber adapted to open said main valve to produce sub- 95
- stantially unrestricted flow of cooling liquid in said circuit, movable shutters associated with the radiator, and means controlled by said valve stem for moving the shutters. 100
7. In combination with an engine cooling system comprising a radiator and a cooling liquid circuit including the engine and radiator, a plurality of intercommunicating chambers included at the upper part of said circuit, one of said chambers having communication with the cooling liquid from the engine, a by-pass thermostat within the latter chamber, a by-pass valve actuatable by said by-pass thermostat for by-passing the liquid to another of said chambers, a valve stem slidably extending through a wall of said chamber, a main valve on said stem, a main thermostat in the second said chamber adapted to open said main valve to produce substantially unrestricted flow of cooling liquid in said circuit, movable shutters associated with the radiator, a lever connected to move the shutters and mounted in the path of said valve stem for actuation thereby. 105
8. In an internal combustion engine cooling system, the combination of a radiator comprising an upper water box, thermally responsive means in said water box for controlling the circulation through said radiator, and shutter mechanism associated with said radiator actuated by said thermally responsive means. 110
9. In an internal combustion engine cooling system, the combination of a radiator comprising an upper water box, a thermally responsive element in said water box, valve means actuated thereby, said thermally responsive element and said valve means being grouped in unit assembly for removal as a unit from said water box, and shutter mechanism associated with said radiator arranged to be actuated by said thermally responsive element. 115
10. In an internal combustion engine cooling system, the combination of a radiator comprising an upper water box, said water box having an opening therein, a shell insertable in said water box through said opening, a thermally responsive element carried by said shell, a valve port in said shell, and a valve actuated by said thermally responsive element for controlling said valve port, said thermally responsive element, valve and valve port being removable with said shell as a unit. 120
11. In an internal combustion engine cooling system, the combination of a radiator comprising an upper water box, said water box having an opening therein, a shell insertable in said water box through said opening, a thermally responsive element carried by said shell, a valve port in said shell, a valve actuated by said thermally responsive element for controlling said valve port, 125
12. In an internal combustion engine cooling system, the combination of a radiator comprising an upper water box, said water box having an opening therein, a shell insertable in said water box through said opening, a thermally responsive element carried by said shell, a valve port in said shell, a valve actuated by said thermally responsive element for controlling said valve port, 130

- said thermally responsive element, valve and valve port being removable with said shell as a unit, a shutter attachment removably mounted on said radiator, and motion transmitting mechanism connecting said thermally responsive element with said shutter attachment, said motion transmitting mechanism being disconnectible to permit removal of said shutter attachment.
- 10 12. In combination with an engine cooling system comprising a radiator and a cooling liquid circuit including the engine and radiator, a chamber located in said circuit above the engine, a second chamber for restricted communication with said first chamber, a plurality of valves for establishing communication between said chambers, a thermostat in said first claimed chamber controlling said valves, a thermostat in said second chamber and shutters actuated thereby to control the circulation of air through said radiator.
- 15 13. In combination with an engine cooling system comprising a radiator and a cooling liquid circuit including the engine and radiator, a chamber located in said circuit above the engine, a second chamber for restricted communication with said first chamber, a plurality of valves for establishing communication between said chambers, a thermostat in said first claimed chamber controlling said valves, a thermostat in said second chamber controlling another valve between said chambers for permitting unrestricted flow through the same, and shutters actuated by said latter thermostat to control the circulation of air through said radiator.
- 20 14. In combination with an engine cooling system comprising a radiator and a cooling liquid circuit including the engine and radiator, a chamber located in said circuit above the engine, a second chamber for restricted communication with said first chamber, a plurality of valves for establishing communication between said chambers, a thermostat in said first claimed chamber controlling said valves, and a thermostat in said second chamber controlling another valve between said chambers for permitting unrestricted flow through the same.
- 25 15. In combination with an engine cooling system comprising a radiator and a cooling liquid circuit including the engine and radiator, a chamber located in said circuit above the engine, a second chamber for restricted communication with said first chamber, a plurality of valves for establishing communication between said chambers, a thermostat in said first claimed chamber controlling said valves, a thermostat in said second chamber controlling another valve between said chambers for permitting unrestricted flow through the same, and shutters actuated by said latter thermostat to control the circulation of air through said radiator.

In witness whereof, I hereunto subscribe my name this 24th day of September, 1925.

HOWARD H. CRAWFORD.
